United States Patent Office.

J. R. ROSE AND EDW. L. CALEY, OF PHILADELPHIA, PENNSYLVANIA, ASSIGNORS
TO COX, WHITEMAN, AND COX, OF SAME PLACE.

Design No. 3,549, dated June 15, 1869; antedated May 25, 1869.

DESIGN FOR A STOVE.

The Schedule referred to in these Letters Patent and making part of the same.

To all whom it may concern:

Be it known that we, J. R. ROSE and EDW. L. CALEY, of the city of Philadelphia, in the State of Pennsylvania, have invented or produced a new and original Ornamental Design for the Body or Fuel-Holder of a Stove, of which the following is a full, clear, and exact description, reference being had to the accompanying drawing, making a part of this specification, and to the letters of reference marked thereon.

Our design consists in the general outline or contour of the body or fuel-holder A B of a stove, together with the ornamental bas-relief configurations thereon.

The said outline or contour is comprised between the upper edge A and the lower edge B of its bottom moulding; and the ornamental configurations consist of the bas-relief figures c-c-c thereon, as shown in the drawing.

What we claim as our invention, and desire to secure by Letters Patent, is—

The ornamented design, herein shown and described, for the body or fuel-holder of a stove.

J. R. ROSE,
EDW. L. CALEY.
